INVENTOR.
James M. Thompson
BY Warren W. House

His ATTORNEY.

UNITED STATES PATENT OFFICE.

JAMES M. THOMPSON, OF KANSAS CITY, MISSOURI.

REFLECTING INSTRUMENT.

Application filed June 29, 1925. Serial No. 40,354.

My invention relates to improvements in reflecting instruments. It is particularly well adapted for use in a dental hand mirror.

5 One of the objects of my invention is to provide a novel instrument of the kind described which will project light from a light source in the instrument to points desired while at the same time shielding the eye of 10 the observer from the direct rays from the light source.

A further object of my invention is to provide a novel instrument of the kind described, which is simple, cheap, compact, 15 convenient, not liable to get out of order, which is durable, and with which the desired light may be easily projected to points desired.

The further object of my invention is to 20 provide a novel construction which may be readily partly disassembled for access to its interior.

The novel features of my invention are 25 hereinafter fully described and claimed.

25 In the accompanying drawing which illustrates the preferred embodiment of my invention as applied to a dental hand mirror,

Fig. 1 is a perspective view of my improved reflecting instrument.

Fig. 2 is an enlarged longitudinal central sectional view of the same.

Fig. 3 is a cross section, enlarged, on the line 3—3 of Fig. 1.

35 Fig. 4 is a cross section on the line 4—4 of Fig. 2.

Fig. 5 is a rear view of the mirror.

Similar reference characters designate 40 similar parts in the different views.

The instrument has a casing comprising a circular body 1 having an externally threaded open end on which is removably fitted a threaded ring 2.

In the body 1 and held thereby releasably 45 by the ring 2 is a mirror comprising a glass plate 3 having a silvered reflecting inner side 4, and provided with an edge, 5, preferably annular and outwardly flaring and bevelled.

50 The body 1 is provided with a handle 6, which is hollow and adapted to contain a battery cell 7 which has connected to it a conductor 8 which is connected to an electric lamp 9 located in the body 1 at the rear 55 of the silvered inner side 4.

The inner surface of the body 1 at 10 is reflecting and outwardly flaring, and disposed so as to reflect light from the lamp 9 against the beveled edge 5, the latter being disposed so as to refract the projected light 60 outwardly, preferably, through the glass plate 3, the rays of light converging, preferably, from the outer surface of the glass plate 3.

The handle 6 has at its outer end a revolvable finger piece 11 fitted in the handle proper, and carrying a contact member 12, which is adapted to strike a contact member 13 with which the outer end of the battery cell 7 is provided. The lamp 9 has one 70 terminal contacting with the body 1. The latter and the handle 6 and finger piece 11 are also conductive, the casing of the cell 7 being nonconductive. By turning the finger piece to and from a position in which the contact member 12 will strike the contact member 13, the circuit will be closed and opened, so as to turn on and off the current from the lamp 9.

When the finger piece is turned to the closed position, the light from the lamp 9 will strike and be reflected by the reflecting surfaces 10 against the beveled edge 5. From there the light will be refracted inwardly and outwardly, as shown in Fig. 3, 85 so as to make a halo of light, when an annular beveled edge is provided. This light will be projected at desired points and reflected therefrom into the mirror in which the operator will see the surface thus reflected.

After the device has been used, the finger piece 11 is turned to the position, shown in Figs. 2 and 4, thus breaking the circuit in which the lamp 9 and battery cell 7 are located.

For access to the lamp to replace the same, or to clean the interior of the body 1, the ring 2 is removed and with it the glass plate 3.

By withdrawing the finger piece from the handle 6, the battery cell may be inserted or removed.

With the use of the instrument, the direct rays of the lamp 9 do not enter the eyes of the operator, and the lamp is carried in a convenient manner.

I do not limit my invention to the structure shown and described, as many modifications, within the scope of the appended

claims, may be made, without departing from the spirit of my invention.

What I claim is:—

1. A reflecting instrument comprising a casing having an inner reflecting surface, a mirror in said casing comprising a glass plate having an outwardly flaring beveled edge and a silvered reflecting inner side, and a lamp in said casing disposed at the rear of said glass plate and so as to throw light against the reflecting surface of the casing, the latter being disposed so as to reflect light from said lamp against said beveled edge and through said glass plate therefrom. 45
2. A reflecting instrument comprising a casing, a mirror in said casing comprising a glass plate having an outwardly flaring beveled edge, and a silvered reflecting inner side, and means disposed at the rear of said mirror by which light may be projected against said flaring beveled edge and forwardly through said glass plate therefrom. 50
3. A reflecting instrument comprising a casing having a handle, a glass plate in said casing having an outwardly flaring refracting edge and a silvered beveled inner side, an electric lamp in said casing at the rear of said glass plate, said casing having means therein for reflecting light from said lamp against said beveled edge and therefrom through said glass plate, and means in said handle and casing for supplying said lamp with current. 55
4. A reflecting instrument comprising a casing having a handle and an inner reflecting surface, a glass plate in said casing having a beveled outwardly flaring edge and a silvered inner reflecting side, an electric lamp in said casing at the rear of said glass plate, said reflecting surface of the casing being disposed so as to reflect light from said lamp against said beveled edge and therefrom through said glass plate, a battery in said handle, and conducting means connecting said battery with said lamp. 60
5. A reflecting instrument comprising a casing, a glass plate in said casing having a beveled edge and a silvered reflecting inner side, and means in said casing for projecting light against said beveled edge, the latter being disposed so as to refract the projected light through said glass plate. 65
6. A reflecting instrument comprising a casing having a body and a ring removably fitted on the body, a glass plate held against said body by said ring and having an annular outwardly flaring beveled edge and a reflecting inner side, a lamp in said body at the rear of said glass plate, and means in said body for reflecting light projected from said lamp against said beveled edge, the latter being disposed so as to refract the projected light through said glass plate. 70
7. A reflecting instrument comprising a transparent plate having at its rear side an opaque coating having a front reflecting surface, the plate having a beveled edge which flares forwardly outwardly, light projecting means at the rear of said coating, and means for reflecting light projected from said projecting means against said beveled edge from which the light so refracted passes through said transparent plate. 75

In testimony whereof I have signed my name to this specification.

JAMES M. THOMPSON.
